I claim the ornamental design for a collapsible accessory basket, as shown and described.

DESCRIPTION

FIG. 1 is perspective view of the collapsible accessory basket wherein the dashed lines depict stitching.

FIG. 2 is a top view of the basket.

FIG. 3 is a bottom view of the basket.

FIG. 4 is a right side view of the basket (the left side view being a mirror image of the right side view).

FIG. 5 is a front elevational view of the basket; and,

FIG. 6 is a rear elevational view of the basket.

The broken lines in FIGS. 1–6 show stitching. The circular features illustrated in FIGS. 1, 2, and 3 represent a type of surface pattern.
